UNITED STATES PATENT OFFICE

HAROLD D. CHURCH, OF CLEVELAND, OHIO, ASSIGNOR TO THE WHITE MOTOR COMPANY, OF CLEVELAND, OHIO, A CORPORATION OF OHIO

LUBRICATING SYSTEM FOR AN INTERNAL COMBUSTION ENGINE

Application filed October 2, 1930. Serial No. 485,899.

This invention relates to a lubricating system for an internal combustion engine.

It is an object of this invention to provide a simple and efficient circulatory lubricating system for an internal combustion engine embodying a radiator or like apparatus for cooling the lubricant used therein.

It is a further object of this invention to provide a lubricating system, as defined in the first object of invention above set forth, in which a leak in the cooling apparatus will neither deplete the system of lubricant, or terminate the delivery of lubricant to the wearing surfaces of the engine.

Further objects of invention will appear in the following description, when read in connection with the accompanying drawing which forms a part of this application, and in which;

The figure is a side elevation, partly in section, of an internal combustion engine provided with a lubricating system embodying this invention.

With the exception of the lubricating system hereinafter described, the engine illustrated in the drawing is of a more or less conventional type. It comprises a cylinder block 10, a crank case 11, an oil pan 12, a cam shaft 13 mounted at one side of the crank case in bearings 14, and a crank shaft 15 mounted in the central portion of the crank case in bearings 16.

Mounted on the side wall of the crank case 11 below the cam shaft 13, there is a pair of oil pumps 17 and 18 driven from the cam shaft by means of a common driving shaft 19. The upper pump 17 is provided with an intake pipe 20, extending downward into the oil pan 12, and communicates through a pipe 21 and a manifold 22 with a plurality of ducts 23 leading to the cam shaft and crank shaft bearings 14 and 16. The lower pump 18 is provided with an intake pipe 24 which extends into the oil pan 12 to a less depth than the intake pipe 20, and which for that reason draws oil from a higher level. It is connected by a pipe 25 with a chamber 26 formed in the upper header of a radiator 27 mounted on the forward end of the engine in the rear of an

engine driven fan 28 which acts to both cool the radiator 27 and a forwardly disposed radiator (not shown) for the engine cooling water. The chamber 26 communicates with a chamber 29 in lower header of the radiator 27 through a tortuous system of conduits comprising a plurality of sets of vertically extending pipes 30 alternately connected at their upper and lower ends by means of chambers constructed within the upper and lower headers of radiator by means of partitions 31. The chamber 29 communicates with the interior of the oil pan 12 through a pipe 32, a pair of serially connected ducts 33 and 34 formed in the bottom wall of the oil pan, and an upwardly directed pipe 35 which extends into the lower flared end of the intake pipe 20.

During operation of the engine, the pump 18 draws from the oil pan 12 a volumetric flow of oil in excess to that drawn up by the simultaneously operated pump 17, delivering the same through the pipe 25 into the radiator 27, and from the radiator 27 through the conduits 32, 33, 34 and 35 into the mouth of the intake pipe 20. The pump 17 draws up a portion of the cooled oil delivered into the mouth of the intake pipe 20 by the pump 18, and delivers it through the pipe 21, manifold 22, and ducts 23 to the engine bearings 14 and 16, from where it flows downward into the oil pan 12. The remaining portion of the oil delivered into the intake pipe 20 by the pump 18 flows back into the reservoir through the annular space intermediate the upper end of the pipe 35 and the circumjacent lower end of the intake pipe 20.

Should the pump 18 fail to deliver a flow of oil into the intake pipe 20, from any cause other than the system having been depleted of an amount of oil sufficient to lower the oil level within the oil pan below the lower end of the pipe 20, the pump 18 will draw oil directly from the oil pan 12 through the annular space existing between the upper end of the pipe 35 and the lower end of the intake pipe 20, delivering the same to the engine bearings 14 and 16 in place of the cooled oil normally delivered thereto.

It is to be noted that the external parts of the system, including the radiator 27, the

pipe 32, and the upper portion of the pipe 25, are so located that a leak created therein can not possibly result in the expulsion from the system by the pump 18 of a sufficient amount 5 of oil to lower the oil level in the oil pan below the intake pipe 20, and that as a result the bearings 14 and 16 will be supplied with oil by the pump 17, notwithstanding that the pump 18 has expelled from the system 10 through a leak in the external parts the maximum amount of oil permitted by the allocation of the external parts.

Although the foregoing description is necessarily of a detailed character, in order 15 that the invention may be completely set forth, it is to be understood that the specific terminology is not intended to be restrictive or confining, and that various rearrangements of parts and modifications in structural details may be resorted to without departing from the scope or spirit of the invention as 20 claimed.

I claim as my invention:

1. In a lubricating system for an internal 25 combustion engine, a lubricant reservoir, means for delivering lubricant from said reservoir to wearing surfaces in said engine including an intake conduit opening into said reservoir, means for returning to said reservoir the lubricant supplied to said wearing surfaces, and means for cooling the oil in said 30 system including a radiator, a conduit communicating at its opposite ends with said reservoir and said radiator designed to convey 35 lubricant from said reservoir to said radiator, and a conduit for conveying lubricant from said radiator communicating at its opposite ends with said radiator and said reservoir, said first named means and said second named 40 means being so arranged and designed that said first named means is supplied by said second named means with lubricant substantially unmixed with the lubricant in said reservoir.

45 2. In a lubricating system for an internal combustion engine, a lubricant reservoir, means for delivering lubricant from said reservoir to wearing surfaces in said engine including an intake conduit opening into said 50 reservoir, means for returning to said reservoir the lubricant supplied to said wearing surfaces, and means for cooling the oil in said system including a radiator, a conduit communicating at its opposite ends with said reservoir and said radiator designed to convey 55 lubricant from said reservoir to said radiator, and a conduit communicating at its opposite ends with said radiator and said reservoir arranged to convey lubricant from said 60 radiator directly into the mouth of the aforesaid intake conduit.

65 3. In a lubricating system for an internal combustion engine, a lubricant reservoir, means for delivering lubricant from said reservoir wearing surfaces in said engines in-

cluding an intake conduit opening into said reservoir, means for returning to said reservoir the lubricant supplied to said wearing surfaces, and means for cooling the oil in said system including a radiator, a conduit for conveying oil from said reservoir to said radiator, and a conduit for conveying oil from said radiator extending into the mouth of the aforesaid intake conduit and communicating with said reservoir through a space intermediate its discharge end and the inner wall of the aforesaid intake conduit.

4. In a lubricating system for an internal combustion engine, a lubricant reservoir, means for delivering lubricant from said reservoir to wearing surfaces in said engine including an intake conduit opening into said reservoir, means for returning to said reservoir the lubricant supplied to said wearing surfaces, and means for cooling the oil in said system including a radiator located outside of said engine above said reservoir, a conduit for conveying lubricant from said reservoir to said radiator communicating at one end with said reservoir at a point above the mouth of the aforesaid intake conduit and at its opposite end with said radiator, and a conduit for conveying lubricant from said radiator communicating at its opposite ends with said radiator and said reservoir, said first named means and said second named means being so arranged and designed that said first named means is supplied by said second named means with lubricant substantially unmixed with the lubricant in said reservoir.

5. In a lubricating system for an internal combustion engine, a lubricant reservoir, means for delivering lubricant from said reservoir to wearing surfaces in said engine including an intake conduit opening into said reservoir, means for returning to said reservoir the lubricant supplied to said wearing surfaces, and means for cooling the oil in said system including a radiator located outside of said engine above said reservoir, a conduit for conveying lubricant from said reservoir to said radiator, communicating at one end with said reservoir at a point above the mouth of the aforesaid intake pipe and at its other end with said radiator, a conduit for conveying oil from said radiator extending into the mouth of the aforesaid intake conduit and communicating with said reservoir through a space intermediate its discharge end and the inner wall of the aforesaid intake conduit, and an engine driven fan for cooling said radiator.

In testimony whereof I hereunto affix my signature this 26th day of September, 1930.

HAROLD D. CHURCH.

CERTIFICATE OF CORRECTION.

Patent No. 1,906,538.

May 2, 1933. 3

HAROLD D. CHURCH.

It is hereby certified that error appears in the printed specification of the above numbered patent requiring correction as follows: Page 2, line 34, claim 1, for "resigned" read "designed"; and line 65, claim 3, after the syllable "ervoir" insert the word "to"; and that the said Letters Patent should be read with these corrections therein that the same may conform to the record of the case in the Patent Office.

Signed and sealed this 23rd day of May, A. D. 1933.

M. J. Moore.

Acting Commissioner of Patents.
